DEPILATORY KIT

Frank Michaels, Mahwah, N.J.
(1449 2nd Ave., New York, N.Y. 10021)

Filed Feb. 4, 1974, Ser. No. 439,414

Term of patent 14 years

Int. Cl. D28—03
U.S. Cl. D86—10 C

FIG. 1

FIG. 2

FIG. 3

FIG. 4

FIG. 5

FIG. 6

FIG. 1 is a front elevational view of a depilatory kit showing my new design;

FIG. 2 is a rear elevational view thereof;

FIG. 3 is an end elevational view thereof;

FIG. 4 is a second end elevational view thereof;

FIG. 5 is a top plan view thereof; and

FIG. 6 is a bottom plan view thereof on a slightly reduced scale.

I claim:

The ornamental design for a depilatory kit, substantially as shown.
